UNITED STATES PATENT OFFICE.

EDWARD M. STILES, OF MOUNT PLEASANT, IOWA.

DEVICE FOR HANDLING DATES, DRIED FRUIT, AND THE LIKE.

1,043,168.

Specification of Letters Patent.

Patented Nov. 5, 1912.

Application filed January 2, 1912. Serial No. 669,033.

To all whom it may concern:

Be it known that I, EDWARD M. STILES, a citizen of the United States, residing at Mount Pleasant, in the county of Henry 5 and State of Iowa, have invented certain new and useful Improvements in Devices for Handling Dates, Dried Fruit, and the Like, of which the following is a specification:

10 This invention relates to improvements in devices, particularly adapted, though not necessarily limited in its use, for handling dates and by means of which the articles may be readily removed from the bulk and 15 placed into packages, without the hand of the operator coming into contact with the articles.

It is a well known fact that dates are put up in boxes generally oblong, and that five 20 sides of the box are removed to expose the dates so that ready access may be had thereto. Heretofore it has been customary to sever the dates from the bulk by means of a date pick in connection with which it is necessary for the operator to employ his free 25 hand for assisting the pick in removing the dates, which is not sanitary.

It is one of the objects of the present invention to provide an improved device by 30 means of which the dates may be readily severed from the bulk and placed into a bag or receptacle without coming in contact with the hands of the operator.

To the attainment of these ends and the 35 accomplishment of other new and useful objects as will appear, the invention consists in the features of novelty in substantially the construction, combination and arrangement of the several parts, hereinafter more 40 fully described and claimed and shown in the accompanying drawing exemplifying the invention, and in which—

Figure 1 is a top plan view of an improved device of this class constructed in 45 accordance with the principles of this invention; Fig. 2 is a side elevation of the device shown in Fig. 1; Fig. 3 is a sectional view taken on line 3—3, Fig. 2.

Referring now more particularly to the 50 drawing and in the form shown, the device consists primarily of a scoop which may be of any desired size and configuration, and constructed of any suitable material. The body of the scoop comprises a base and sides 55 which are constructed of spaced tines or prongs 10. These tines or prongs are con-

nected at one extremity by means of a member 11, which is preferably solid and of any suitable thin sheet material which serves as a back for the scoop and also as 60 a means for holding the tines or prongs in proper position and spaced with respect to each other. The free extremities of the tines are pointed or sharpened as at 12 to permit their ready insertion into the bulk of 65 the articles. The back 11 has connected with it in any suitable manner, a handle 13 by means of which the tool may be transported or manipulated.

Slidably supported in any suitable 70 manner, so that it may be moved freely within the scoop, is an ejector 14, preferably in the form of a solid plate which is of a size to substantially fill the space within the tines and prongs, and this ejector 14 75 may be manipulated in any suitable manner, preferably by means of a handle 15 which is connected by one extremity with the ejector and passes loosely through a suitable aperture or opening in the member 11, and the 80 free extremity of the handle 15 is preferably deflected as at 16 to form a stop. This handle 15 may be of any desired length, but is preferably of such a length that when the ejector 14 reaches the free extremities of 85 the tines or prongs 10, the deflected extremity 16 of the handle will abut the end member 11 to form a stop for the ejector. If desired, the ejector may be provided with suitable apertures 17, any number of which 90 may be provided and through which the tines or prongs loosely pass so that they will form a guide and support for the ejector. Obviously, these apertures or 95 openings may be omitted, if desired, as the ejector will be retained in position by means of the tines engaging the edges of the ejector, and the handle 15 which slides through the end member 11. In use, and assuming the parts to be in the position 100 shown in Figs. 1 and 2, the operator grasps the handle 13 and may also grasp the handle 15 which will hold the ejector 14 in position, it being understood that the ejector 14 is first positioned by the operator according to the amount of the article it is desired to remove from the bulk.

The operator then forces the tool or device into the bulk of the dates, this operation being readily accomplished owing to 110 the fact that the points of the tines or prongs are sharp, and when the tool has

been inserted, a sufficient distance into the bulk of the article, a portion of the bulk may be readily removed, and will be retained in the tool. When the articles are 5 still held by the tool, the operator may then insert the end of the tool or device into the open end of a bag designated at 18 in dotted lines in Fig. 1, and when thus inserted, the operator may release the handle 15 and retain hold of the handle 13 with one hand, and then with the other hand force the ejector 14, by means of the handle 15, in a direction to discharge the articles from the tool and into the receptacle.

10 15 With this improved device, it will be manifest that the hands of the operator do not come in contact with the article being dispensed, and if the required amount is not taken up by the tool or device in the first 20 operation, the operation may be repeated until the desired amount has been removed.

25 Obviously, the operator may position the ejector at any point in the scoop, and when positioned, will be held against accidental adjustment by the hand of the operator with which he grips the handle 13.

What is claimed as new is:

30 1. In a device of the class described, the combination of a scoop-shaped body, comprising spaced prongs straight throughout their entire length, an end member with which the prongs are connected, a handle connected with said end member, an ejector within the scoop and a handle connected 35 with the ejector, the last recited handle having a slidible bearing in the end member, said bearing being disposed entirely within the peripheral edge of the end member and spaced some distance from the said edge at 40 all points of the edge for protecting and holding the second recited handle out of engagement with the commodity in any position of the tool.

45 2. In a device of the class described, the combination of a scoop-shaped body comprising spaced prongs straight throughout their entire length, an end member with which the prongs are connected, a handle connected with the said end member, an 50 ejector within the scoop, and a handle connected with the ejector, the last said handle being substantially parallel with the first

recited handle and extending through the end member at a point entirely within and spaced for some distance from the peripheral edge of the member at all points of the said edge for holding the second recited handle out of contact with the commodity in any position of the tool, the second recited handle being spaced from the first said handle and in a position to be grasped by the operator when the first recited handle is grasped.

3. In a device of the class described, the combination of a scoop shaped body, comprising spaced prongs straight throughout their entire length, and an end member with which the prongs are connected, an ejector within the scoop and a handle connected with the ejector, the said handle having a sliding bearing in the end member, said bearing being disposed entirely within the peripheral edge of the end member, and spaced some distance from said edge at all points of the edge for protecting the handle and holding it out of contact with the commodity in any position of the tool.

4. In a device of the class described, the combination of a body upon the surface of which the articles are supported, the body comprising spaced sharpened prongs straight throughout their entire length and an end portion with which the prongs are connected, and which portion is arranged at an angle to the prongs to project beyond the face of the prongs, and a handle connected with the ejector, the said handle having a sliding engagement with the said end portion and passing loosely therethrough, said ejector being disposed substantially within the plane formed by the peripheral edge of the body and end portion and said handle being also disposed within said edge and spaced from the edge for some distance at all points of the edge for protecting the handle and holding it out of contact with the commodity in any position of the tool.

In testimony whereof I have signed my name to this specification, in the presence of two subscribing witnesses, on this 26th day of December A. D. 1911.

EDWARD M. STILES.
